Attorney

UNITED STATES PATENT OFFICE.

THEODORE JOHNSON, OF ERIE, PENNSYLVANIA.

SHARPENER.

Application filed April 18, 1922. Serial No. 555,359.

To all whom it may concern:

Be it known that I, THEODORE JOHNSON, a citizen of the United States, residing at Erie, in the county of Erie and State of Pennsylvania, have invented new and useful Improvements in Sharpeners, of which the following is a specification.

This invention is particularly designed to sharpen knives, particularly knives for household use.

The invention is illustrated in the accompanying drawings as follows:

Fig. 1 shows a front elevation of the device,

Fig. 2 a side elevation,

Fig. 3 a section on the line 3—3 in Fig. 1,

Fig. 4 a section on the line 4—4 in Fig. 2,

Fig. 5 an elevation of the sharpening blades,

Fig. 6 a section on the line 6—6 in Fig. 5, and

Fig. 7 a view showing the locking devices.

The frame is made up of the plate 1 which is secured to a wall by a screw *a*. This plate has a hook or bend 2 at its bottom and a cover plate 3 is secured between the front face 2 and the rear wall of the frame in any convenient manner. As shown it has tongues 5 which extend through the frame 1. The ends of this cover plate are bent down at 4 forming a closure for the ends of the frame. A rotatable mounting 6 extends across the frame between the end pieces 4, a screw 7 extending into one end of the mounting 6 through a perforation 8 in the end plate 4, the opposite end having a screw 9 extending through a perforation 10 in the opposite end plate 4, the screw 9 having wings 9^a by means of which the mounting may be readily rotated. Sharpening blades are in the form of wheels 11. These are provided with openings 12 which fit the mounting 6. Preferably this mounting is of locking contour in cross section which as exemplified in the drawings is square so that the wheels are locked on the mounting or shaft 6. Radially extending arms 13 are arranged on the wheels. These arms preferably have beveled edges 14 so as to form a cutting edge which will more readily effect the sharpening action on the knife. A locking plate 15 is arranged at the end. It is similar in form to the other plates except that it is thin and of resilient material. It is adapted to pass over slight protuberances 16 formed by stamping one of the end plates 4. These

protuberances are yieldingly engaged by the arms 15 so as to lock the mounting in different positions. A slot 17 is provided in the plate 3 and end pieces 4.

The arms 13 and alternate wheels 11 are in staggered relation forming passes 18 between the opposing sharpening edges of the arms. It will be noted that there are at least two arms on one side of the pass so that in passing an implement along the pass the implement is supported in line with the pass. The locking plate 15 is adapted to bring one of these passes into register with the slot 17 with each locking position. A knife as shown in dotted lines at 19 is drawn through the pass 18, thus effecting a sharpening action of the blade. As the edges of one pass become dull or ineffective the wheel may be turned to bring the next succeeding pass into register with the slot 17, thus providing a renewed pass with new sharpening edges.

What I claim as new is:

1. In a sharpener, the combination of a mounting, and a series of plates carried by the mounting with arms extending alternately forming between them a pass, said pass extending in a direction at right angles to the faces of the plates, and the plates forming a plurality of arms with cutting edges at one side of the pass.

2. In a sharpener, the combination of a mounting having a cross-section of locking contour, and a series of wheels having perforations fitting the mounting locking each wheel independently with the mounting, said wheels having arms extending radially from the mounting, the arms being alternately offset circumferentially forming axially directioned passes with sharpening edges at each side of the passes.

3. In a sharpener, the combination of a rotating mounting, said mounting having a cross-section of locking contour, and a series of sharpening wheels on the mounting, said wheels having perforations fitting the mounting and locking each wheel independently with the mounting, said wheels having radially extending arms with sharpening edges circumferentially offset to form a plurality of axially extending passes with sharpening edges at each side of the passes.

4. In a sharpener, the combination of a rotating mounting, said mounting having a cross-section of locking contour, a series of sharpening wheels on the mounting, said

- wheels having perforations fitting the mounting and locking each wheel independently with the mounting, said wheels having radially extending arms with sharpening edges circumferentially offset to form a plurality of axially extending passes with sharpening edges at each side of the passes, a frame carrying the mounting, and means for holding the mounting against turning.
- 5 10 15 20 25 30 35 40
6. In a sharpener, the combination of a rotating mounting, a series of sharpening wheels on the mounting having radially extending arms with sharpening edges circumferentially offset to form a plurality of passes with sharpening edges at each side of the passes, a frame carrying the mounting, and a yielding plate arranged on the mounting having arms yieldingly engaging projections on the frame.
7. In a sharpener, the combination of a rotating mounting, a series of sharpening blades carried by the mounting, a frame in which the mounting is journaled, said frame comprising a back plate having a forward and upward bend, and a cover plate arranged between the upward bend and back plate with downturned ends and having a slot through which an article being sharpened may be passed.
- In testimony whereof I have hereunto set my hand.

THEODORE JOHNSON.
